UNITED STATES PATENT OFFICE.

HARRY W. LOWE, OF FLORENCE, NEBRASKA.

HEATING APPARATUS FOR CANNING-MACHINES.

1,129,698.

Specification of Letters Patent. Patented Feb. 23, 1915.

Application filed April 13, 1914. Serial No. 831,654.

To all whom it may concern:

Be it known that I, HARRY W. LOWE, a citizen of the United States, residing at Florence, in the county of Douglas and State of Nebraska, have invented certain new and useful Improvements in Heating Apparatus for Canning-Machines, of which the following is a specification.

The object of the present invention is the provision of means whereby to quickly and uniformly heat fruits and similar materials in the process of canning and the invention is found to be of particular advantage in the steam cooking of tomatoes in the preparation of catsup.

In carrying out the invention I employ a system of heating pipes within a kettle, the pipes being endless, preferably circular and having intercommunication between the several pipes whereby the units are similarly disposed relative to the source of heat supply and thus equally heated to a uniform extent throughout as distinguished from the usual heating coils having dead ends. The pipes are moreover advantageously nested within each other and disposed in vertical tiers so that the heating effect is distributed more generally throughout the mass of material undergoing treatment than by heating systems heretofore in use.

In the accompanying drawing and in the following detailed description is set forth a preferred embodiment of the invention. As, however, the invention is capable of embodiment in other and varied forms of construction it is to be understood that the drawing and description should be construed in an illustrative and not in an unnecessarily limiting sense.

40 In the drawings—Figure 1 is a top plan view of the heating pipes, the kettle not being shown; and Fig. 2 is a vertical section on the line 2—2 of Fig. 1.

Having reference to the drawings in detail, the reference numerals 11 and 12 designate respectively the upper and lower units of a set of heating pipes provided on opposite sides with intercommunicating passages at 13 and 14. Each of the pipe units 45 is preferably annular and steam is admitted thereto by way of the passage 14 from a supply pipe 15 containing a valve 16. The two pipes 11 and 12 are in practice made substantially the same size and of a diameter 50 adapted to fit loosely within the kettle 16 at a slight distance from the walls thereof

and below the level of the materials therein. Inside of the set of heating units above described is disposed a second set preferably independent thereof and composed of the three units 17, 18 and 19. The two units 17 and 18 being of dissimilar size and arranged the latter within the former, both being in substantially the same horizontal plane as the unit 12 of the outer set, while the unit 19 of the inner set is of a diameter slightly less than the unit 17 and greater than the unit 18 and occupies a position above the two units 17 and 18 and in substantially the horizontal plane of the outer unit 11. The three units comprising the inner set are provided at opposite sides with intercommunicating passages 20 and 21, which passages occupy substantially the relative position of the sides of a triangle, the three units which they connect being likewise triangularly disposed as viewed in cross section. The inner set of heating units is provided with a steam supply 22 which is common to the three units and which is equipped with a control valve 23. Each set of pipes is provided with a drain-cock 24.

When either the valve 16 or 23 is open heating fluid is supplied in substantially uniform quantity to the outer or inner set of heating units as the case may be, the fluid flowing by means of the endless construction of heating pipes to all parts of the same which are heated to a substantially uniform degree. By the proper manipulation of the valves and supplying the heating fluid in greater or less quantity to the different sets of heating units according to the circumstances the mass of material within the kettle can be uniformly and quickly brought to and maintained at the proper temperature to secure the best results.

I claim:

1. In heating apparatus, a plurality of endless single coil pipes horizontally arranged in nested relation, and provided at intervals with substantially unobstructed intercommunicating passages, and a supply pipe common to more than one of said pipes, at least one of said intercommunicating passages being independent of the passage incident to said common supply pipe.

2. In heating apparatus, a plurality of endless single coil pipes horizontally arranged in nested relation and provided at intervals with intercommunicating passages of a diameter substantially equal to the in-

- terior diameter of said pipes, and a supply pipe common to more than one of said pipes, at least one of said intercommunicating passages being independent of the passage incident to said common supply pipe.
3. In heating apparatus, a plurality of endless single coil pipes in nested relation and in superposed tiers and provided at intervals with substantially unobstructed intercommunicating passages, and a supply pipe common to more than one of said pipes, at least one of said intercommunicating passages being independent of the passage incident to said common supply pipe.
4. In heating apparatus, an endless single coil pipe intercommunicating with a second endless single coil pipe in superposed relation therewith, and a supply pipe common to said pipes and discharging at a point substantially midway between said pipes.
5. In heating apparatus, a plurality of intercommunicating, endless, single coil pipes in substantially concentric relation and another endless single coil pipe in a different plane from the plane of said first named pipes and in communication with all of said first mentioned pipes.
6. In heating apparatus, the combination of a set of two intercommunicating pipes horizontally arranged in superposed relation and provided with a supply pipe common to both, and a second set of three intercommunicating pipes horizontally arranged in nested relation within the first set and triangularly disposed as viewed in cross section, the three provided with a common supply pipe, substantially as described.
7. In heating apparatus, the combination with a receptacle, of a plurality of endless single coil pipes horizontally arranged in nested relation and provided at intervals with substantially unobstructed intercommunicating passages, and a supply pipe common to more than one of said pipes, at least one of said intercommunicating passages being independent of the passage incident to said common supply pipe.
8. In heating apparatus, the combination with a receptacle, of a plurality of intercommunicating endless single-coil pipes horizontally arranged therein in superposed relation, a second set of intercommunicating endless pipes horizontally arranged in superposed relation within the first set, and means to supply a heating medium to the members of each set in common and to the two sets independently, substantially as described.
9. In heating apparatus, the combination with a receptacle, of a set of two intercommunicating annular pipes horizontally arranged therein in superposed vertical relation, a second set of three intercommunicating pipes horizontally arranged within the first set in superposed triangular relation, a supply pipe common to the members of the outer set, and a second supply pipe common to the members of the inner set, substantially as described.
10. In heating apparatus, the combination with a receptacle, of a set of two intercommunicating single-coil pipes horizontally arranged in superposed relation and provided with a supply pipe common to both, and a second set of three intercommunicating single-coil pipes horizontally arranged in nested relation within the first set and triangularly disposed as viewed in cross section, the three provided with a common supply pipe substantially as described.
11. In heating apparatus, a set of three intercommunicating single-coil pipes horizontally arranged in nested relation and triangularly disposed as viewed in cross section, the diameter of the coil forming the apex of the triangle being less than that of one of the others and greater than that of the third.

In witness whereof I have hereunto signed my name in the presence of two witnesses.

HARRY W. LOWE.
